SELF VENTING DISPENSING SPOUT

Richard W. Beall, Jr., Hermosa Beach, Calif.

Application March 10, 1955, Serial No. 493,529

8 Claims. (Cl. 222—479)

The present invention relates generally to the field of liquid dispensers, and more particularly to a liquid dispenser that is self-venting and seals automatically. This application is an improvement over my co-pending application Serial No. 384,376 filed in the United States Patent Office October 6, 1953, now Patent No. 2,779,517, issued January 29, 1957.

The major object in devising the present invention is to provide a liquid dispenser that can be removably affixed to such containers as drums, carboys, tanks and like commercial vessels, by means of which liquid may be discharged therefrom at a controlled rate, which dispenser is self-vented due to the fact that a constant atmospheric pressure is maintained thereby within the container on which it is mounted.

Another object of the invention is to supply a dispenser that automatically assumes and maintains a liquid seal for the container with which it is associated until application of a fluid discharge force is applied thereto.

A further object of the invention is to furnish a dispenser that allows for discharge of the fluid contents of an industrial container as required, with the contents of the container being subjected to a minimum of atmospheric contact.

A still further object of the invention is to provide a dispenser that may be opened and closed without the use of tools, that is easy to mount on or remove from a container, and which eliminates the possibility of inadvertent or accidental fluid discharge from the container.

Yet another object of the invention is to provide a dispenser that permits liquid to be freely poured from a container within a minimum of time without undesirable wasteful splashing and gurgling thereof, which dispenser prevents any appreciable escape of volatile vapors from the fluid contents of the container on which it is mounted.

Another object of the invention is to furnish a dispenser that is ideally suited for use on containers in which inflammable liquids or fluids having dangerous physical characteristics are stored, due to the spring means associated with the dispenser which at all times urges and maintains same in closed position whereby it cannot inadvertently assume an open position without application of actuating force that must be constantly maintained thereon to effect a continuing flow of fluid from the container.

A further object of the invention is to supply a dispenser that eliminates the necessity of opening a vent in a container on which it is mounted in order to discharge fluid therefrom.

These and other objects and advantages of the present invention will become apparent from the following description of a preferred and alternate form thereof, taken in conjunction with the accompanying drawings illustrating those forms, in which:

Figure 1 is a perspective view of the fluid dispenser of the present invention shown removably mounted on a gasoline container;

2

Figure 2 is a vertical, cross-sectional view of the dispenser;

Figure 3 is a plan view of the invention;

Figure 4 is a fragmentary perspective view of the upper portion of the device;

Figure 5 is a vertical, cross-sectional view of the alternate form of the invention;

Figure 6 is a vertical cross-sectional view of a first alternate form of the invention;

10 Figure 7 is a vertical cross-sectional view of a second alternate form of the invention;

Figure 8 is a vertical cross-sectional view of a third alternate form of the device; and

15 Figure 9 is a vertical cross-sectional view of a fourth alternate form of the invention.

Referring now to the drawing for the general arrangement of the invention, it will be seen that a fluid container C is provided in which a tapped bore R is formed that is removably engaged by a threaded portion P of the dispenser D. Container C may be of any desired size or shape as long as it is adapted to be so positioned that liquid may drain therefrom through the bore R.

20 A fluid discharge opening A is formed in threaded portion P, which opening is defined by a body shoulder B and communicates with a tubular pouring spout S. Spout S slidably supports within its confines a spring-loaded sleeve T which embodies a normally sealed air vent V as well as a liquid sealing member M that removably contacts shoulder B. An actuating handle H

25 is rigidly affixed to sleeve T, and upon application of manual force thereon above a predetermined value, the sleeve moves inwardly relative to spout S whereby the vent V is then in communication with the atmosphere and the member M displaced from shoulder B. When handle H is moved downwardly to position Y shown in phantom line in Figure 2, and then slightly rotated, the sleeve T can be removably locked in a predetermined longitudinal position relative to the spout S whereby liquid may be discharged through spout S without

30 gurgling, for in order to equalize the pressure in the container relative to atmospheric pressure during fluid discharge from the container, it flows inwardly through vent V without coming into contact with an oppositely moving liquid from spout S.

35 In detail, portion P and spout S are preferably fabricated as an integral unit, and portion P includes a cylindrical plug 10 in which threads 12 are formed on the exterior surface thereof. A ring 14 extends outwardly from plug 10 and is disposed above threads 12. Ring 14 has a flat under surface 16 which grips a washer 18

40 disposed on the upper surface of top 20 of the container to effect a fluid-tight seal therewith when the plug is screwed in bore R. As may be seen in Figure 2, ring 14 also has a circular flange 22 extending upwardly therefrom. A number of circumferentially spaced lugs 24 are rigidly affixed to flange 22 and project outwardly therefrom. Lugs 24 can be grasped manually or by means of a suitable turning tool (not shown) to screw the plug 10 into or out of position in bore R.

45 Pouring spout S is formed from a rigid tubular member which extends upwardly from plug 10, and a bore 28 is provided in tubular member 26 that extends downwardly through ring 14 into plug 10 to define a circular body shoulder 30 with a counterbore 32 of slightly larger diameter than bore 28. Three vertically disposed slots 34 extend downwardly in tubular member 26 from the upper circumferential end thereof, each of which slots terminates in a relatively short horizontal extension 36 that terminates in a slightly enlarged portion 36a. The

50 three slots 34 which are identical in shape, are preferably spaced from one another by 90°.

55 Sleeve T includes a rigid tube 38 of such external

diameter as to snugly and slidably engage the interior surface of tubular member 26. Tube 38 has the handles H rigidly mounted thereon. In detail, handles H are four rigid arms 40 which are horizontally disposed and rigidly affixed to the upper exterior surface of tube 38. Three of the arms 40 are so disposed as to extend outwardly through slots 34 and be vertically movable therein. The four arms 40 are preferably formed with enlarged vertically disposed end portions 40a, which arms (Figure 2) rigidly support a horizontally positioned ring 42 which slidably engages the exterior surface of tube 38.

A helical spring 44, preferably fabricated from flat resilient stock, is provided that is sufficiently long to at all times be in compression when disposed in an encircling position about pouring spout S. When so situated the upper end portion 44a of spring 44 abuts against the under side of ring 42, and the lower end portion 44b thereof disposed on the upper annulus shaped surface 42a of plug 10 that is situated between tubular member 26 and flange 22.

The lower end portion of tube 38 has threads 50 formed thereon that engage a tapped recess 52 that extends downwardly from the upper surface 54 of an annular sealing member 56. A washer 58 formed of a resilient sheet material that is impervious to the solvent action and the chemical characteristics of the liquids that will be held in container C is bonded to the surface 54 of the sealing member.

A vertically extending wall 60 occupies an intermediate position within the confines of tube 38, and extends the length thereof. Wall 60 subdivides the interior of tube 38 into two longitudinally extending passages, the first of the passages being vent V, and the second passage 61 being of somewhat larger transverse cross section than vent V to permit an appreciable amount of liquid in container C to flow therethrough.

The upper end of tube 38 has an end piece 62 extending thereacross. The end piece has an air inlet port 64 formed therein that is in communication with vent V, and a tapped liquid discharge port 66 through which liquid can flow from the second passage 61. Tube 38 has an elongate opening 68 formed in the lower side portion thereof opposite vent V, and the opening being in communication with the fluid passage 61. A transversely disposed bore 70 is formed in the lower portion of tube 38, with the bore establishing communication between vent V and counterbore 32 in plug 10.

The use and operation of the preferred form of the invention is extremely simple. When the dispenser is mounted on a container C as previously explained in detail, the spring 44 at all times tends to expand to move the ring 42, sleeve T, and sealing member M upwardly. Upward movement of the assembly is limited by the resilient sealing washer 58 being brought into pressure contact with the lower surface B of plug 10. This pressure contact of washer 58 not only prevents liquid flowing from the inside of container C to pouring spout S, but prevents entry of air from the atmosphere through vent V and bore 70 to contact the liquid held in the container.

It will be apparent that upon a downward force of the required magnitude being exerted on handle H, the sleeve T, vent V, sealing member M and sealing washer 58 are moved downwardly relative to pouring spout S. Liquid can now flow from the inside of container C through opening 68 to the second passage 61, and from this passage through tapped bore 66 to the pouring spout S.

By moving the handle H downwardly until the arms 40 are disposed at the position Y shown in phantom line in Figure 2, and then slightly rotating the handles, the arms can be caused to be disposed in enlarged slot extensions 36a. The arms 40 when so disposed cause the sleeve T, vent V, member M and sealing washer 58 to be so situated relative to plug 10 and pouring spout S,

as shown in phantom line in Figure 2 that the maximum rate of flow of liquid from the inside of container C can take place from the invention.

A first alternate form of the dispenser is shown in Figure 5. A cylindrical shell 80 is provided that has a plate 82 normally disposed to the interior surface thereof and intermediately situated between the ends of the shell. Plate 82 rigidly supports a first tubular member 84 that extends downwardly through an opening 85 formed in a wall 88 that defines the container C' in which the liquid is disposed. Tubular member 84 is formed with an upwardly and inwardly extending tapered circumferential edge portion 86. An annular liquid sealing member 88 is supplied that has an upwardly and inwardly tapered circumferential edge 88a that is adapted to set against edge portion 86 and effect a liquid seal therewith.

Liquid sealing member 88 closes the lower end of a second tubular member 90 that is slidably mounted in the first tubular member 84. Second tubular member 90 as may be seen in Figure 5 is formed with a curved upwardly disposed portion 92 from which liquid can be discharged. A longitudinally extending intermediately disposed wall 94 divides the interior of the second tubular member 90 into an air vent 96 and a liquid discharge passage 98. Air is admitted into vent 96 through an inlet port 100 formed in the curved portion 92 and discharged from the lower part of the vent through a discharge port 102 formed in first tubular member 84.

An inverted cap shaped housing 104 that includes a downwardly extending side wall 106 is provided, and is affixed to the exterior surface of second tubular member 90 in such a manner that the side wall 106 overlaps the upper portion of shell 80, and a helical spring 107 that is at all times in compression is situated in the confined space 108 defined by side wall 106 and shell 80. The spring 106 is of upwardly and inwardly tapering configuration, and has the lower edge thereof resting on the upper surface of plate 82 and the upper edge of the spring abutting against the interior surface of housing 104.

The use and operation of the alternate form of the invention is extremely simple. When sufficient manual force is exerted on housing 104 to move it downwardly, the second tubular member 90 is concurrently moved downwardly therewith, and liquid sealing edge 88a separated from tapered edge 86, liquid in container C' can now flow into liquid passage 98 through an opening 109 formed in the lower portion of second tubular member 90. Atmospheric air flows inwardly into container C' through vent 96 and port 102 as liquid is discharged from the container, to equalize the pressures between the interior and exterior of the container, and thus prevent gurgling of the liquid as it is discharged from spout 92. Of course, upon the actuating force being removed from housing 104, the spring 107 expands, and the edges 86 and 88a are brought together into liquid sealing contact. In this manner, communication between liquid passage 98, air vent 107, and the interior of container C' is blocked until the housing 104 is again moved to an actuating position.

A second alternate form of the invention is shown in Figure 6 in which it will be seen that a tubular liquid discharge member 120 is provided. An intermediately positioned valve body 122 that rotatably supports a plug 124 divides member 120 into an outwardly disposed portion 120a and an inwardly situated portion 120b. Portion 120a is formed with a downwardly extending outer end 120c. Portion 120b is provided with threads 120d on the free end thereof.

A tubular air vent defining member 126 is positioned above liquid discharge member 120 and follows the general contour thereof. Vent member 126 is also divided by valve body 122 into an outwardly disposed portion 126a and an inwardly disposed portion 126b, which latter has threads 126d formed therein. In addition it will be noted that portion 126b extends inwardly beyond the

termination of portion 120b to prevent air passing inwardly through the vent from mixing with liquid flowing outwardly through the liquid discharge member.

Plug 124 has two parallel, vertically spaced, transverse bores 130 and 132 formed therein that can be concurrently brought into alignment with the interior of portions 120a, 120b and portions 126a, 126b, respectively. Plug 124 may be rotated by means of a handle 134 rigidly affixed to the upper portion of the plug. Inadvertent displacement of plug 124 from the valve body is prevented by the use of a downwardly extending threaded rod 136 that projects through a bore in a plate 138 that covers the lower portion of valve body 122. A nut 140 engages rod 136 and abuts against the exterior surface of plate 138.

The second alternate form of the invention provides a valve in which an air vent passage is formed and terminated concurrently with the opening and closing of the valve by use of handle 134. This alternate form operates in the same manner as the preferred form, except that the control valve therefor is positioned on the exterior of the liquid container with which it is used.

A third alternate form of the invention is shown in Figure 7 which differs from the second alternate form only in that a continuous tubular liquid discharge member 120' and tubular air vent defining member 126' is employed therein. The outer ends of members 120', 126' are slightly curved, and are concurrently opened and closed by pivotal movement of a convex-concave valve member 142. Valve member 142 is provided with two laterally separated legs 144, the inner end portions of which are pivotally supported by screws 146 rigidly affixed to liquid discharge member 120'. A handle 148 is mounted on valve member 142 that is utilized in moving the valve member to an open or closed position.

The fourth alternate form of the invention is illustrated in Figure 8, and is particularly well adapted for use with a relatively large liquid container, such as a five gallon can or fifty gallon drum (not shown). The top 160 of a container is shown in this figure which is provided with a liquid outlet generally designated by the numeral 162. Outlet 162 includes a short, cylindrical shell 164 that projects outwardly from the circumferential edge portion of top 160 and defines a liquid outlet opening 166. Shell 164 terminates at its outermost end in an annular bead 168, which shell is adapted to receive and hold a resilient ring 167 within the confines thereof. A longitudinally extending first recess 170 is formed on the interior surface of ring 167 that is preferably of rectangular transverse cross section, or at least has a flat circumferentially extending interior surface 167a.

Two oppositely disposed, longitudinally extending recesses 172 are formed on the interior surface 167a of ring 167 and preferably located 90° from the first recess 170. A combined pouring spout and air vent 174 is provided which is slidably mounted within the confines of ring 167. This combination spout and vent 174 is preferably fabricated as an integral unit from one of the numerous commercially available synthetic plastic materials suitable for this purpose, the selection of which is determined by the fact that it will not be physically or chemically affected by the fluids to be dispensed therethrough. It will also be seen in Figure 8 that the combined spout and vent includes an elongate tubular member 176 in which a longitudinally extending transverse wall 178 is formed that defines an air vent 180. The surface 178a of wall 178 and the interior surface 176a of the tubular member define a bore 182 through which liquid is discharged. Vent 180 has a portion 183 that extends beyond the end 184 of tubular member 176 and is disposed within the container for the same reasons previously outlined in connection of those forms of the invention shown in Figures 6 and 7.

As illustrated in Figure 8, tubular member 176 has a longitudinally extending rib 177 formed on the exterior

surface thereof, which rib leads to a transversely disposed sealing ring 188 also formed on the exterior of the tubular member. Rib 177 is slidably mounted in recess 170 and permits longitudinal movement only of the combination spout and air vent 174 in shell 164.

Two oppositely disposed arms 179 are pivotally supported on the exterior surface of tubular member 176 by pins 179a, which arms are of such transverse cross section as to permit slidable movement thereof when inserted within the confines of recesses 172. Arms 179 project beyond the end of shell 164 and are connected to opposite circumferential edge portions of an annular cap 185. Cap 185 (Figure 8) includes an annular plate 184 from the circumferential edge of which a continuous circular side wall 187 depends to terminate on the outer end thereof in a flange 188. At least a portion of flange 188 extends inwardly and is adapted to removably engage the inner face 190 of bead 168. Cap 185 as well as arms 179 are fabricated from a plastic material which has some rigidity, but is still sufficiently resilient to permit placement of the cap in that position shown in phantom line.

When arms 179 are in alignment with and in the same plane as that of the longitudinal axis of shell 164, the tubular member 174 can be moved inwardly sufficiently to permit the cap 185 to removably engage the shell as shown. When member 174 is in the solid line position of Figure 8, cap 185 removably effects a liquid and vapor-tight seal with shell 164. Liquid cannot escape through the recesses 172 during pouring thereof, nor can air enter the confines of the container, for as liquid is poured from the container, ring 188 abuts against the inner surface of top 160 completely obstructing communication between the container interior and the outer atmosphere.

When cap 185 is in a liquid sealing position on bead 168, it seals the outwardly disposed positions of recesses 172 and prevents passage of liquid or outside air therethrough. From the above description it will be seen that the ring 188 serves a dual purpose; that of sealing the inwardly disposed ends of recesses 172 as liquid is poured or discharged from the container, and that of serving as a stop to limit the maximum outward movement of tubular member 174 relative to shell 164. Cap 185 also serves a dual purpose in that it seals the combination air vent and pouring spout 174 and prevents inadvertent movement thereof relative to liquid outlet 162. The operation of the fourth alternate form of the invention is the same as that of the preferred form when it is in a liquid dispensing position.

A possible variation in the fourth alternative form of the invention is to position a helical spring that is at all times under compression in an encircling position around the combined spout and air vent 174. The lower end of the spring rests on the upper surface of the resilient ring in which the spout and vent 174 is slidably mounted. The upper end of the spring is affixed to the exterior surface of the spout-and-vent combination, which spring at all times urges it outwardly toward a pouring position in substantially the same manner in which the preferred form of the invention functions. It will, of course, be realized that this spring-loading of the combination spout and vent only results in outward movement thereof when the resilient cap is not in locked position on bead 168 or outlet 162.

The fifth alternate form of the invention shown in Figure 9 is particularly adapted for use in discharging liquid from drums or other containers (not shown) that include a wall 190 in which a tapped bore 192 is provided through which fluid is discharged. Another tapped bore (not shown) is normally provided for such containers and is usually positioned in that side portion of wall 190 opposite to the discharge bore 192. This second tapped bore serves as an air vent during the time fluid is being discharged through bore 192. When liquid

is shipped or stored in a container of this type, both tapped bores are closed by threaded plugs (not shown) that can be easily removed therefrom by means of a socket wrench or the like.

In using the fifth alternate form of the invention, but one plug is removed from one of the tapped bores 192. This form includes a cylindrical body 194 having threads 196 formed on the exterior surface thereof that can be caused to removably engage the tapped bore 192 to establish communication with the liquid in the container. A cylindrical support 195 projects outwardly from body 194 for reasons that will be explained hereinafter. The support is formed with a circumferentially extending groove 195a on the interior surface thereof. A bore 198 extends through body 194 and support 195, in which bore a combination liquid discharge spout and air vent generally denoted by the numeral 200 is slidably mounted. The combined spout and vent embodies a tubular member 202, a straight portion 202a of which is slidably mounted in bore 198, and a downwardly and forwardly curved portion 202b of which at all times projects outside the confines of bore 198. A resilient ring 199 situated in groove 195a that slidably engages the exterior surface of portion 202a effects a fluid-tight seal therewith.

A longitudinally and transversely disposed wall 204 is provided inside the combined spout and vent that divides the interior thereof into a liquid dispensing passage 206 and air vent passage 208. A cap 210 of any desired construction closes the inwardly disposed end of member 202 and extends outwardly beyond the exterior surface thereof. When the cap 210 is positioned against the inwardly disposed edge of body 194, it serves as a stop to limit the maximum forward movement of the combination spout and vent member 200.

It will be seen in Figure 9 that a transverse port 212 is formed in the inwardly disposed portion of member portion 202a, which port communicates with passage 206. However, when the combined spout and vent 200 is in its forwardmost position as shown in solid line, port 212 is sealed out of communication with the container interior as it resides within the confines of body 194. A relatively large opening 214, preferably of substantially the same area as that of the vent passage 208, is formed in member portion 202a. This opening 214 is sealed from communication with the interior of the container as it is situated within body 194 when the device is in the position shown in solid line.

The threaded body 194 has two oppositely disposed legs 194a projecting forwardly therefrom that support pins 216 or other suitable means on which pairs of links 220 are pivotally mounted. A rigid ring 222 is affixed or transversely formed on the combined vent and spout portion 202a, forwardly from legs 194a. Pairs of links 224 are pivotally mounted on pins 226 projecting outwardly from ring 222. The free ends of links 220 and 224 are pivotally joined by pins 228, as may be seen in Figure 9. The upwardly and outwardly extending link in each pair of links 224 continues by means of an extension 224a to a position above the combination vent and spout where the extensions 224a are brought together to form a common forwardly extending handle 230.

A helical spring 232 is provided that is at all times in compression and encircles the combined vent and spout portion 202a. The inwardly disposed end of spring 232 abuts against the forward face of body 194, and the forward end of the spring bears against the rear face of ring 222. It will be apparent that with this construction the bore 212 and opening 214 are at all times maintained out of communication with the container interior except when the handle 230 is moved in a counter clockwise direction as shown. Upon such movement of the handle, the combined spout and vent 200 is moved inwardly into the confines of the container sufficiently to bring bore 212 and opening 214 into com-

munication therewith. Liquid then flows outwardly through passage 206 and air moves inwardly from the outside atmosphere through passage 208 to replace the liquid as it discharges from the container. As the volume of air entering the container is the same as the volume of the withdrawn liquid, the pressure on the inside and outside of the container are at all times equalized whereby fluid flows from the combined spout and vent without gurgling or giving rise to any other physical manifestations that might cause splashing or splattering of the liquid.

In order to attach a hose to the outer extremity of the combined spout and vent 200, or to provide a resilient liquid conduit by means of which liquid may be transferred into a particular container, a tubular liquid discharge member 240 is provided. Member 240 has a rear portion 242 in which a transverse circular rib 243 is formed on the interior thereof. Portion 242 swages down to a forward part 244 considerably smaller in interior diameter. A transverse wall 245 is provided inside member 240 which divides the interior thereof into an air vent passage 208' and a fluid carrying passage 206'. Vent passages 208 and 208', and passages 206 and 206' communicate with one another when member 240 is disposed on the combined spout and vent member 200.

Member 240 is preferably held on the outer end of the combination spout and vent by the use of a transverse, circumferentially extending groove 248 formed in the member near the end thereof. Due to the resilient nature of the material from which it is fabricated, member 240 can then be slipped on the end portion of the combined spout and vent where it is removably held in position thereon by rib 243 positioned in groove 248. Threads 250 formed on the exterior of part 244 permit a hose (not shown) to be removably connected thereto.

While the dispensers disclosed herein are primarily intended for use for the purposes hereinbefore mentioned, it has been found by experience that the invention works very successfully as a filling device. Consequently, when it is desired to refill a container or other receptacle on which the invention is mounted, there is no necessity of first removing same or to provide separate filler means, since it may be actuated to open the passage means therethrough whereby the liquid may be introduced into the spout. The invention operates in the same manner as when used for dispensing liquids, except that the flow of liquid and air is reversed so that liquid displaces the air within the container.

Although the dispensers herein shown and described are fully capable of achieving the objects and providing the advantages hereinbefore mentioned, it is to be understood that they are merely illustrative of the presently preferred embodiments of the invention, and that it is not intended to limit same to the structural details herein shown and described other than as defined in the appended claims.

The invention claimed is:

1. An automatic sealing and self-venting device for use on a container to dispense liquid therefrom including: a first tubular liquid discharge member that has a plurality of circumferentially spaced longitudinally extending slots formed therein which terminate in transverse slot extensions; a mounting member for maintaining said first member in a liquid dischargeable position with said container interior; a second tubular liquid discharge member longitudinally movable in said first discharge member; liquid sealing means mounted on said second member, which sealing means is adapted to effect a liquid-tight seal with said first member when said second member occupies a first predetermined position relative to said first member; a plurality of circumferentially spaced transversely disposed arms mounted on said first member that are movably mounted in said slots and slot extensions, with said arms being capable of partial rotation to engage said extensions and maintain said second member at a

second predetermined position where said sealing means does not effect a liquid seal with said first discharge member; an air vent member mounted on said second discharge means, which air vent member only establishes communication between the interior and exterior of said container when said second discharge means is not in said first predetermined position; and spring means that at all times tend to maintain said second discharge means in said first predetermined position.

2. A dispenser as defined in claim 1 in which said air vent member is formed by a longitudinally extending, intermediately disposed wall situated inside said second member that terminates on one end at the inner face of said sealing means, and said wall and second member cooperating to define a passage through which air can flow from the atmosphere to a transverse bore formed in said second member above said sealing means, and said bore being in communication with the interior of said container only after said second member has been moved to a position apart from said first predetermined position.

3. A dispenser as defined in claim 1 in which said air vent member is a longitudinally extending passage defined in the structure of said second member, said passage terminating on one end in an abutting position against an inwardly positioned face of said sealing means, said passage in communication with a transverse bore formed in said second member above said sealing means, and said bore in communication with the interior of said container only after said second member has been moved to a position apart from said first predetermined position.

4. A dispenser as defined in claim 3 in which said mounting means includes an outwardly extending first ring, and said spring means being a helical spring that encircles said first member and is at all times in compression, with one end of said spring abutting against said first ring, and the other end of said spring exerting an upward force on said second discharge means.

5. A dispenser as defined in claim 4 in which said

arms that engage said slots support a second ring that slidably engages the exterior surface of said first member, and said helical spring has the upper end portion thereof in contact with the lower face of said second ring.

5 6. A dispenser as defined in claim 4 in which a resilient washer is provided that is mounted on the upwardly disposed face of said liquid sealing means, and said washer being subjected to a compressive liquid sealing action between said sealing means and mounting means

10 when said arms are not disposed in said slot extensions.

15 7. A dispenser as defined in claim 6 in which said slot extensions are formed with enlarged end portions that extend above the upper edges of said extensions and in which said arms can be removably disposed when said sealing means is disposed in said second predetermined position, said end portions and said spring cooperating to maintain said sealing means in said second predetermined position until said second discharge means is manually moved to dispose said arms in said vertically

20 extending slots.

25 8. A dispenser as defined in claim 6 wherein handle means are mounted on said second ring to permit said arms to be rotated into and out of engagement with said slot extensions.
